HOLDING MEANS FOR KNITTING MACHINE ELEMENTS

Kenneth Howie, Norristown, Pa., assignor to
Wildman Mfg. Co., Norristown, Pa., a corporation of Pennsylvania

Application July 27, 1936, Serial No. 92,913

11 Claims. (Cl. 66—109)

The invention relates to means for holding in prescribed position elements of a knitting machine, or knitting apparatus, such as knock-over bits, needles of a needle bar, or the points of a welt or transfer bar.

One object of the invention is to provide holding means of such character and form as will accommodate itself to and compensate for irregularities in the structure or dimension of the elements, or take care of irregularities arising from any cause, such as the manufacture of said elements, or the parts cooperating therewith, or such irregularities as may arise from differences in strains imposed on some of the elements in respect to the degree of strain imposed on other elements of the same set.

I illustrate the invention as an example in connection with knock-over bits of a flat knitting machine, such as is used for making full fashioned hosiery, but it will be understood that my invention is not limited to these particular elements, but may be employed in any situation where a plurality of elements are intended to bear a prescribed relation to other like elements of the same set.

In the accompanying drawing

Figure 1 is a cross sectional view of a knock-over bit assembly with my invention associated therewith;

Fig. 2 is a cross sectional view of the compensating strip, or holder; and

Fig. 3 is a plan view of Fig. 2, partly broken away to show the rubber center of said strip.

In this drawing, 1 indicates the knock-over bit of ordinary form supported by a bed 2 of brass or like material, which bed, or bar, is provided with grooves indicated by dotted lines at 3 in which the knock-over bits lie.

The knock-over bits have projections 4, as in ordinary practice, engaging a longitudinally extending groove 5 of the supporting bar, or bed, 2.

Cooperating with the bar 2 is a clamp, or cover plate, 6, which, as in ordinary practice, may be of steel, the purpose of this bar being to clamp the knock-over bits in prescribed positions in the supporting bar 2, for which purpose the clamping plate is held in place by screws, one of which is indicated at 7.

The compensating bar, or strip, is indicated at 8, located between the front edge portion of the cover plate and the upper edges of the knock-over bits. This compensating strip is composed of a rubber center in the form of a strip, indicated at 9. This rubber strip center is enclosed in a casing which preferably is in the form of a

sheet a of comparatively soft metal, such as brass, which surrounds the rubber center, both as to its top and bottom faces and its edges. This enclosing casing is formed in one piece of metal bent upon itself, the joint between the free edges of the metal being located at the point 10, which is at the rear of the strip, whereas the front edge of the strip would be entirely closed by the intact portion of the thin sheet brass member.

At the rear edge of the composite strip where the free edges of the metal come together, one edge of the metal is provided with a small flange turned inwardly, and the lower ply of the sheet metal indicated at 11 underlies this small flange, which is indicated at 12.

By having the joint between the upper and lower portions of the sheet metal located at the rear of the compensating strip, the said strip will tend to free itself from oil that might lodge upon the parts. This compensating strip will take care of the irregularities above mentioned, so that if, for instance, any knock-over bit is not an accurate fit in relation to the cooperating holding parts, the pressure of the cover plate will cause said strip to compensate for this irregularity and exert pressure upon this knock-over bit and hold it firmly in place. On the other hand, if any knock-over bit is slightly larger than its prescribed size, the compensating strip will yield at this point and allow the clamping plate to assume its proper position so as to efficiently cooperate with the holding organization to retain all of the knock-over bits in their prescribed positions.

The metal casing being of soft pliable material will have a compensatory effect within itself, and this will be added to by the rubber center. With a bit that is slightly too high at its shank portion, the rubber will distort lengthwise of the strip and accommodate itself, and thus allow the holding or compensating strip to perform its holding action in relation to the other bits of the series.

The invention is also of material advantage when replacing a damaged or worn bit with a new bit, because the strip will accommodate itself to any slight difference in this new bit in respect to the old bits mounted in the bar or bed piece.

The rubber being non-compressible, but distortable, will have a tendency to recover itself, as conditions may require.

I claim:

1. In combination with knitting machine ele-

- ments, holding means therefor comprising a bed and a cover member between which the elements are clamped, and a compensating strip interposed between the clamping member and the elements, said strip consisting of a center strip of renitent material and a casing of sheet material for said center strip.
2. Holding means according to claim 1 in which the renitent material is rubber.
- 10 3. Holding means for knitting machine elements according to claim 1 in which the casing for the renitent center strip is composed of pliant metal.
4. Holding means for knitting machine elements according to claim 1 in which the casing for the renitent center strip is of soft metal.
5. Holding means for knitting machine elements according to claim 1 in which the casing for the elastic center strip is of sheet brass.
- 20 6. In combination with knock-over bits of a flat knitting machine, a bed therefor, a clamping plate, and a compensating strip between said clamping plate and the upper edges of the knock-over bits composed of a rubber strip center and a sheet metal casing enclosing said center, substantially as described.
- 25 7. A compensating strip for holding knitting

elements of a knitting machine, comprising a center strip of renitent material and an enclosing casing of sheet metal bent upon itself to form upper and lower layers with one edge closed, the free edges of the metal sheet being brought together at the other edge of the strip.

8. A compensating strip according to claim 7 in which one of the free edge portions of the metal strip is bent upon itself to provide a lip or flange to receive the edge of the renitent strip, substantially as described.

9. A compensating strip for holding knitting elements of a knitting machine comprising a center consisting of a strip of rubber and a casing for said yielding material composed of sheet material.

10. A compensating strip for holding knitting elements of a knitting machine according to claim 9 in which said casing is of sheet material having substantially the qualities of sheet brass, substantially as described.

11. Apparatus according to claim 1 in which the sheet material is folded to present a front closed edge, the joint between the free edges of the sheet material being at the rear of the strip, substantially as described.

KENNETH HOWIE.
